WILLIAM HARRIS AND CLINTON BROWNING, OF RUSH RUN, OHIO.

Letters Patent No. 61,537, dated January 29, 1867.

IMPROVEMENT IN NUT.

The Schedule referred to in these Letters Patent and making part of the same.

TO ALL WHOM IT MAY CONCERN:

Be it known that we, WILLIAM HARRIS and CLINTON BROWNING, of Rush Run, Jefferson county, State of Ohio, have invented a new and useful Improvement in Nuts; and we do hereby declare that the following is a full, true, and exact description thereof, reference being had to the accompanying drawings, forming a part of this our specification, and that the same is sufficiently clear and exact to enable any person skilled in the art to make and practise our invention.

The object of our invention is the formation of a "nut," which shall possess the quality of resistance to "unscrewing" by reason of the trembling, shaking, or jarring to which nuts are subjected under many circumstances of their use, and especially when used upon railroads, or machinery connected therewith.

In Figure 1 of the drawings we have shown a screw-plate, B, having a screw, *c*, set therein, and upon which, for illustration of our invention, we show our improved nut A applied.

The nut A we make in the ordinary form and in the usual way, except that in the process of its formation a slot, which may be of dove-tail form, is cut through one of its sides, as indicated in fig. 1, in which slot or groove a stop or brace, D, is inserted, and held in place by driving down a portion of the nut with a cold chisel against it. The groove or recess which receives the stop D can readily be made by the same act of the machinery which punches the nut in case the nut is machine-made, as is now ordinarily the case. The stop D may be made in the form represented in blue tint in fig. 1, and should have a spring temper, one portion of it being set in the groove of the nut, as at *e*, flush with one of the sides of the nut, while its curved portion *f* extends outwardly therefrom, as represented in said figure. It will thus be seen that when the nut A is rotated in the direction of the red arrow, the point *f'* of the stop D will impinge upon the surface or face *g* of the plate B; when the nut is screwed up; and that as the point *f'* of the stop D is made to extend below the bottom face of the nut, such impingement will spring the portion *f* in the direction of its curve, and thus offer a very great tension resistance to the unscrewing of the nut when the nut is fully screwed down upon the face *g* of the plate B.

In Figure 2 we have shown a wrench adapted for use with our improved nut. This wrench H is made in usual form, but has an angular slot, as at *i*, cut in its inner portion of sufficient capacity to receive the spring *f* of the stop or detent D when applied to the nut, as shown in

Figure 3, said last-named figure being a plan view of the nut detached from the screw *c*.

Figure 4 is an inverted view of fig. 3, and by it the action of the wrench upon the spring *f* in the act of unscrewing is illustrated; that is to say, suppose the wrench to be applied to the nut, as in fig. 4, while the nut is screwed up upon the plate B and it is desired to unscrew it. To effect this, the wrench is turned in the direction indicated by the blue arrow, fig. 1, which act will bring the shoulder *k* of the wrench (fig. 2) in contact with the rear or convex portion of the spring *f*, and thus force its point *f'* to release its bite upon the face *g* of the plate B in advance of the point of time at which the jaws *l l* of the wrench firmly gripe the sides of the nut, thus relieving the nut from the action of the spring in the act of unscrewing.

We would observe, that, having made an improved nut as specified, we deemed it proper in connection therewith to show an improved wrench for operating it, which wrench we do not claim now, as it forms the subject-matter for an independent patent.

Having thus described our invention, what we claim as new, and desire to secure by Letters Patent of the United States, is—

The nut A, in combination with the stop D, provided with a spring point, *f*, constructed and arranged to operate substantially as and for the purpose set forth.

WILLIAM HARRIS,
CLINTON BROWNING.
